(57) **CLAIM**

The ornamental design for a watch case as shown and described.

DESCRIPTION

1. Watch case

1.1 : Perspective

1.2 : Top

1.3 : Bottom

1.4 : Right

1.5 : Left

1.6 : Front

1.7 : Back

No protection is sought for the features of the design indicated by broken lines, shown in the representations; the line shading in the drawings is a drawing convention to represent contours and does not illustrate surface ornamentation or decoration.
